FIG. 2.

FIG. 6.

FIG. 4.

FIG. 5.

UNITED STATES PATENT OFFICE.

DAVID HESS, OF SNAKE RIVER, WASHINGTON.

STORMPROOF COAT.

Application filed January 13, 1925. Serial No. 2,170.

To all whom it may concern:

Be it known that DAVID HESS, a citizen of the United States, residing at Snake River, in the county of Franklin and State 5 of Washington, has invented certain new and useful Improvements in Stormproof Coats, of which the following is a specification.

This invention relates to wearing apparel 10 and particularly to new and useful improvements in storm coats, providing a novel means whereby water, wind and dust cannot penetrate the coat.

Another important object of the invention 15 is to provide a coat of such character, that although storm proof from the elements, it will still be ventilated and flexible throughout the various parts.

A still further object of the invention is 20 to provide a coat of the above mentioned character, which is simple in construction, inexpensive, strong, durable and well adapted for the purposes for which it is designated.

25 Other objects and advantages of this invention will become apparent during the course of the following description.

In the accompanying drawings forming 30 a part of this specification and in which like numerals designate like parts throughout the same:

Figure 1 is a plan view of my coat.

Figure 2 is a section on the line 2—2 of 35 Figure 1.

Figure 3 is a section on the line 3—3 of Figure 1.

Figure 4 is a section on the line 4—4 of Figure 1.

Figure 5 is a fragmentary view of a portion 40 of the coat showing the overlapping parts.

Figure 6 is an enlarged view, partly broken away, to show one of the laps or 45 waterproof elements of the coat.

In the drawings forming a part of this specification, the numeral 1 designates the body of my improved coat to which is secured the arms 2. The coat is provided with a collar 3 and the front edges overlap and 50 are adapted to be buttoned together, as shown at 4. In other words, this coat in general appearance is similar to the ordinary form of overcoat.

In forming my improved coat, I provide 55 first a backing cloth 5 which is formed preferably of some light weight and durable ma-

terial, such as would enable air and ventilation to pass therethrough. Secured to this backing cloth by stitching or other preferred means are a plurality of strips of waterproof material designated by the numeral 6. These strips are secured to the backing cloth along their upper edges as shown by the numeral 7 in spaced relation and the strips are of such width as to overlap, as clearly shown in 60 Figs. 1 and 5 of the drawings. The lower edges of these strips are scalloped to present a neat appearing and attractive design.

As will be seen in Figure 4, the overlapping strips 6 are so arranged with respect to one 65 another that there is substantially a triple overlap, giving the greatest possible protection to the body of the wearer but the securing of these strips to the backing cloth 5 in spaced relation obviously provides a 70 space between each strip to permit ventilation to pass therethrough.

This idea of providing strips of spaced 75 waterproofed material overlapping one another is carried out in both the body and 80 the arms of the coat, thus providing a thoroughly waterproof garment. The spacing of the strips on the backing cloth provides means for the admission of air through 85 said cloth in order to properly ventilate said coat when applied to the wearer. It is a well known fact that great difficulty has been experienced heretofore in providing a thoroughly waterproof coat which would 90 permit of ventilation. The wearers of waterproof coats become greatly overheated and perspire to a considerable degree due to the fact that these ordinary waterproof coats are not capable of ventilation.

In order to carry out the design of the 95 coat with the scalloped lower edges on the strips, I also provide on the collar 3 a strip 6 which does not in itself provide for any ventilation but, as stated, continues the design of the body and arms of the coat. The 100 scalloped edges of the strips 6 give the effect of scales, such as are found on the body of a fish, and in addition to providing an effective design, these scalloped edges tend to shed the water, and elements from the coat 105 when it is worn. The water rolling from one strip to the other will obviously be more readily cast off from the coat with these scalloped edges, than would be true if the edges were straight.

110 From the foregoing description of the construction of my improved coat, it will

be seen that I have provided a means for 5
waterproofing a garment and at the same
time permitting of ventilation therethrough.
The spacing of the overlapping strips on
the backing cloth provides means whereby
the air may enter under the overlapping
strips and pass through the backing cloth.
I have further provided a lining 8 for the
coat which is preferably of the usual lining
10 cloth or material, the same extending
throughout the body and arms of the garment,
being applied in the usual or any
preferred manner.

It will be seen from the foregoing, that
15 I have provided a simple, inexpensive and
efficient means for carrying out the objects
of the invention, and while I have particu-
larly described the elements best adapted
to perform the functions set forth, various
20 changes in form, proportion and in the
minor details of construction may be re-
sorted to, without departing from the spirit
or sacrificing any of the principles of the
invention.

25 Having thus described my invention, what
I claim is:—

A garment made up of a fabric, the fab-

ric including a cloth backing, a series of
strips stitched to the backing and extending
circumferentially around the body of the 30
garment, said strips having straight upper
longitudinal edges and scalloped lower lon-
gitudinal edges, the lines of stitching being
located adjacent the upper straight edges
of the strips, the lines of stitching being 35
spaced from each other whereby the strips
overlap each other, the lines of stitching
and the scalloped edges extending circum-
ferentially around the body of the garment,
an inner strip having its line of stitching 40
lying under the intermediate portion of the
next adjacent strip and between the inner
points of the scalloped edge and the longi-
tudinal straight edge thereof, and the line
of stitching of the said inner strip lying 45
under the free edge portion of an outer strip and
disposed approximately parallel with the
longitudinal edge thereof and intersecting
the curved line of the scalloped edge por-
tion of the said outer strip. 50

In testimony whereof I affix my signa-
ture.

DAVID HESS.
